DESIGN FOR A SHAMPOO CHAIR

Flora H. Ellinger, Chicago, Ill.

Application December 19, 1942, Serial No. 109,071

Term of patent 14 years

To all whom it may concern:

Be it known that I, Flora H. Ellinger, a citizen of the United States, residing at Chicago, in the county of Cook and State of Illinois, have invented a new, original, and ornamental Design for a Shampoo Chair, of which the following is a specification, reference being had to the accompanying drawing, forming part thereof.

In the drawing:

Fig. 1 is a front and side perspective view of a shampoo chair, embodying my new design; and

Fig. 2 is a top plan view of the shampoo chair of Fig. 1.

I claim:

The ornamental design for a shampoo chair, substantially as shown.
